(57) **CLAIM**

I claim the ornamental design for a lower back support brace, as shown and described.

DESCRIPTION

FIG. 1 is a front view of the lower back support brace in unfolded position showing my new design, with shorter hook and loop fastener surface; and,

FIG. 2 is a rear view thereof.

The evenly spaced broken lines on claimed surfaces and zig zag broken lines depict claimed stitching. The pattern on the surface of the article in dashed lines is claimed surface pattern.
